ABRADING APPARATUS

Walter L. Keefer, Hagerstown, Md., assignor to
 Pangborn Corporation, Hagerstown, Md., a corporation of Maryland

Application January 14, 1946, Serial No. 641,095

20 Claims. (Cl. 51—9)

1

This invention relates to abrading apparatus and more particularly to a machine for bringing objects to be cleaned into the path of a high velocity stream of abrasive material.

The invention has particular application to the cleaning of castings, to remove the scale and sand which adheres to them as they come from the mold. The abrasive material, generally in the form of small metallic granules, is projected at the castings at considerable velocity to break loose this foreign matter. It will be apparent, however, that objects other than castings may be subjected to this cleaning action of the abrasive stream.

Various machines have been devised in the past to carry or suspend the articles to be cleaned and bring them into the path of the abrasive stream and then carry them out of the stream. These machines, however, have generally been of complex and therefore expensive construction, and have required a large floor space.

An object of the present invention is to provide a machine which is of relative simple construction but which results in effective cleaning of the articles it handles.

Another object of the invention is to provide a machine of this type which is of relatively simple construction because it is practically reduced to the essential elements of a blasting station and a work loading and unloading station. The invention, however, contemplates the additional provision of a touch-up station at which the articles can be further cleaned by a manually directed blast stream.

Another object of the invention is to proportion the concentration of the stream to the cleaning requirement of the articles as they are disposed in the blast stream. In this respect, the blast stream is caused to play upon the articles for a longer period of time during the portion of their travel at which they are moving at the greatest speed, as this compensates for the tendency for uneven cleaning to occur.

In general, the apparatus of the invention includes a hanger from which a plurality of articles to be cleaned are suspended. This hanger does not travel while it is being loaded or unloaded and this facilitates the manual handling of the articles.

After the hanger is loaded, it is moved into

2

the path of the blast stream and the travel of the hanger is then stopped but it is rotated to bring the articles into the blast stream. While the hanger is being rotated, the blast stream is moved back and forth to cause the abrasive to strike all surfaces of the articles.

The machine provides more than one hanger so that one may be in the blast station while another is in the loading or unloading station.

10 By having a third hanger, a second blasting or touch-up station may be provided. It is not necessary to have more than these three hangers and three stations.

The machine also includes the partitions for 15 isolating the several stations from each other and these partitions travel with the hangers in accordance with the invention.

A preferred embodiment of the invention is 20 illustrated in the accompanying drawings but it is to be understood that the invention is not limited to the details of this construction.

In these drawings:

Fig. 1 is a front elevational view of the portion 25 of the complete apparatus which is above floor level.

Fig. 2 is a plan view of Fig. 1, portions being broken away to show the construction.

Fig. 3 is a section on the line 3—3 of Fig. 2.

The housing of the machine includes a portion 30 of a generally cylindrical side wall 10 and an overlying top wall 11. These walls should be of relatively heavy sheet metal and may be assembled in any desired manner as by riveting or welding. As is apparent from Fig. 2, the side wall 10 does not make a complete circle, but is 35 slightly more than 240° in arcuate extent.

This open portion of the side wall 10 provides the loading and unloading station. At about 40 120° therefrom, in the form shown, the side wall 10 is also removed to form an opening indicated at 12. This opening 12 communicates with a vestibule portion of the housing formed by two arcuate walls 13—13. The walls 13 are of the same radius of curvature having a common center. The top wall 11 overlies the walls 13—13 45 to form a covering for the vestibule. This vestibule contains the abrasive throwing apparatus, as will be explained later.

The side wall 10 is also removed to form an opening 14 which is about 120° from the opening

12 in the form shown. This opening 14 enters into a side chamber having side walls 15 and the top wall 11 overlies the walls 15 to complete the enclosure. Access should be had to this side chamber through an outer door. This chamber, as will be explained, is provided in the form shown to accommodate the attendant who is to "touch-up" the cleaned articles by applying a blast to the foreign matter still adhering to them, if and when required.

The housing rests upon a grating 16 and may be held in fixed position thereon by any suitable means. This grating 16 is preferably at floor level. The grating 17 at the bottom of the vestibule having side walls 13 is lower than the grating 16, as appears from Fig. 3. This increased depth is to accommodate a blasting machine, as will later appear.

Disposed within the housing and along the axis of the side walls 10, is a vertical shaft 20. This shaft 20 is rotatably mounted at its lower end upon a supporting antifriction bearing 21. The inner raceway of bearing 21 is supported upon a stud 22 mounted upright in a reinforced portion of the grating 16. A beam 23 may be positioned beneath the stud 22 to further carry the load.

At the upper end of the shaft 20 is a cap 24 and from the top of this cap extends upwardly a bearing pin 25. Pin 25 is rotatably mounted in a bearing 26 which is affixed to the top wall 11 of the housing. As here shown, the vertical shaft 20 is a tubing to reduce its weight, but this is not necessary.

Projecting radially from the shaft 20 in the illustrative embodiment are three arms 28. As here shown they are attached to the cap 24 and this may be by any means, as welding. These arms 28 are at the upper end of the shaft 20 and are 120° apart in the form shown. As here shown the arms 28 are each made up of spaced side rails having a block 29 between them at their outer ends, but they can be solid or be of other construction.

Within the outer end of each of the arms 28 is rotatably mounted a shaft 31. This shaft 31, in the arrangement shown, passes vertically through the block 29 and is held therein against downward movement by any suitable means. The upper end of shaft 31 has a cross slot 32 therein to be engaged for driving the shaft 31, as will later appear.

Secured to the lower end of each shaft 31 is a work holder 33 made up in the form of a spider having a plurality of radial arms. These arms have notches 34 along their upper faces to receive hooks by which the articles to be cleaned, are suspended. A hook 35 is beneath the axis of the holder 33 to receive a large object to be cleaned.

As a feature of the preferred form of the invention, the holder 33 which is in the blast stream is rotated about its axis. This is accomplished by means of a driven shaft 36 and a jaw clutch 37. The jaw clutch 37 is keyed to the shaft 36 and is movable up and down along the shaft to bring the jaw clutch 37 out of, or into engagement with the shaft 31. When the clutch 37 is moved downwardly it engages the slot 32 in shaft 31 to rotate it.

Jaw clutch 37 is moved up and down by a lever 38 pivoted at 39 to a bracket on the top wall 11 of the housing. A pin 40 at one end of the lever 38 enters a circular groove 41 around the jaw clutch 37. At its other end the lever 38 is

pivoted to a hinging link 42 by which the attendant may move the jaw clutch 37 up and down. To retain the link 42 in the position in which clutch 37 is engaged or disengaged, it is formed with two openings 43 Fig. 1, which may engage a pin 44 projecting from the housing.

Shaft 36 is driven through a gear reduction box 46, and a belt drive 47, by a motor 48. When it is desired to move the work holder 33 which is in the blast stream, to the next station, the jaw clutch 37 is first moved upwardly. After the next work holder is brought to the blasting station, the jaw clutch 37 is moved downwardly to engage and drive it.

15 Disposed midway between each pair of work holders 33, is a partition 50. These partitions are attached to the vertical shaft 20 and project radially therefrom. Braces 51 extend between the partitions 50 and the arms 28 to interconnect 20 and afford a mutual support between them. The partitions are large enough to extend nearly to the side wall 10, the top wall 11, and the floor grating 16.

25 Flexible material 52 is attached to the outer vertical edges of partitions 50 to bear against the side wall 10 and form a seal. Similar sealing strips 53 and 54 are affixed to the top and bottom edges of the partitions 50 to bear against the top wall 11 and grating 16, respectively. Due to 30 the presence of these partitions 50, each work holder 33 is segregated within its own chamber when in the blast stream. The sealing strips 52, 53 and 54 around the edges of the partitions prevent the escape of abrasive from this particular chamber in which blasting is occurring.

35 Handles 55 are affixed to opposite sides of each partition 50 to be grasped in rotating the entire assembly consisting of the central shaft 20, the arms 28 and their work holders 33, and the partitions 50. While it is intended that this indexing be done manually by pushing or pulling on these handles 55, it will be apparent that power means may be utilized to index the rotating assembly to move the article holders 33 to their successive positions.

45 It is important to accurately position the article holders 33 as each one is brought to the blasting station, in order that its shaft 31 will be in line with the jaw clutch 37 to be driven thereby. To obtain this accurate positioning, stop means are provided and this includes a movable stop arm 57 against which may bear an adjustable screw 58 on each partition 50. The stop arm 57 is attached to a shaft 59 which is pivoted in a box-like receptacle 60 affixed to the side wall 10 close to the hanging link 42. The shaft 59 extends outside of the receptacle 60 and is bent to form a handle portion 61 by which the shaft 59 may be rotated.

60 Ordinarily, the stop arm 57 will be in the downward position shown, so that it will be struck by the adjustable bolt 58 to limit the rotation of the partition 50 as it is advanced. By screwing each bolt 58 in or out and then locking it in this position, accurate indexing will be obtained for each article holder. When the work holders are to be advanced, the shaft 59 is turned by means of its handle portion 61 so as to turn the stop arm 57 to an upper position in which it enters 65 the receptacle 60 and is out of the way of the partitions 50.

70 It has been stated that the vestibule having side walls 13, houses the abrasive throwing apparatus which projects the abrasive against the articles to be cleaned. This abrasive is pro-

jected through the opening at 12 in the side wall 10 of the housing and against the articles suspended from the particular work holder 33 which is in the blasting station.

As here shown the abrasive throwing apparatus is a plurality of machines 63 and 64 which serve to propel the abrasive by the action of centrifugal force. A suitable machine which operates on this principle is disclosed in Patent No. 2,320,364 issued to Walter L. Keefer on June 1, 1943. However, any other device which delivers abrasive at high velocity and in a concentrated stream, may be utilized. As here shown there are four of the abrasive throwing machines 63 and 64, but this is not a necessary number.

In the form shown a plurality of the abrasive throwing machines are mounted upon a vertically disposed plate 65 within the vestibule. Secured to the lower end of plate 65 and centrally of the width of the plate is a block 66 from which depends a stub shaft 67. The stub shaft 67 is supported by an antifriction bearing 68 mounted in a socket in a pedestal 69. The pedestal 69 may be supported in any suitable manner.

To the upper end of plate 65 is secured a block 71 from which a shaft 72 projects vertically upwardly in axial alignment with the stub shaft 67. This shaft 72 is rotatable in a bearing 73 mounted on the top wall of the housing and the shaft extends above the top of this bearing 73. The stub shaft 67 and shaft 72 therefore serve as trunnions to rotatably support the plate 65.

It is important that the axis of the shaft 72 and stub shaft 67 be coincident with the axis of the side walls 13 of the vestibule in which plate 65 is located. The vertical edges of plate 65, as a consequence, may extend close to the walls 13 and sealing strips 74 attached to these edges remain in contact with the walls 13 as the plate 65 is pivoted about its axis of rotation.

The upper two abrasive throwing machines 63 are driven by a motor 75 carried on a standard 76. This standard 76 and the bases of these two upper abrasive throwing machines 63 may be attached in fixed positions to the plate 65. The lower two abrasive throwing machines 64 and the standard 77 mounting their driving motor 78, preferably are adjustably attached to plate 65 for up and down movement. By this adjustment, the lower machines 64 may be raised or dropped in position to blast shorter or longer articles being cleaned.

From Fig. 3 it will be apparent that each of the two upper blast machines 63 are so disposed that they throw the abrasive in an overhand relationship between the arrows 80 whereas the two lower blast machines 64 are disposed to throw the abrasive in an underhand manner between the arrows 81. Because of this arrangement the two upper blast machines 63 throw abrasive in a generally downward direction so that they will blast upwardly facing surfaces as well as the vertical faces. The two lower blast machines 64 throw abrasive in a generally upward direction so that they will blast downwardly facing surfaces and the vertical faces. As a consequence all horizontal, vertical and angularly disposed surfaces of the work pieces will be cleaned.

As the upper blast machines 63 throw abrasive generally downwardly as appears from arrows 80, and the lower blast machines 64 throw abrasive generally upwardly as appears from arrows 81, their streams would clash if they were in the same plane. To avoid this clashing, the two upper blast machines 63 are displaced laterally from the two lower blast machines 64. As a consequence

the vertical plane containing the two upper streams 80 is sideways from the vertical plane containing the two lower streams 81 and clashing does not occur.

It has been pointed out that the particular article holder 33 in the blasting station is rotated about the axis of the shaft 31, but is not bodily transported or advanced until the cleaning is completed. The rotation of the article holder 33 brings all the articles into the blast streams, but as a further feature of the invention the blast streams are oscillated back and forth across the full width of the articles suspended from the holder 33. Thus, referring to Fig. 2, the blast streams are oscillated back and forth between the lines 82.

The blast streams 80 and 81 are oscillated between the limits indicated by lines 82, by oscillation of the plate 65 carrying the abrasive throwing machines 63 and 64. This is accomplished by oscillating the shaft 72 by means of an arm 83 attached to its upper end. A connecting link 84 is pivoted to the outer end of arm 83 and joins it to the outer end of a crank arm 85.

Crank arm 85 is continuously rotated about a complete circle by its attachment to a shaft 86 projecting from a speed reducing gear box 87. Gear box 87 is driven through a belt drive 88 by a motor 89. The throws of the crank arm 85 and 30 of the arm 83 are so proportioned to each other that the abrasive throwing machines 63 and 64 will swing to such an extent as to move their blast streams back and forth between the lines 82. If desired these throws can be adjustable to permit 35 regulation of the angular space between lines 82. By this means the centrifugal projector is manipulated so as to turn the ends of its rotor axis alternately toward and from the work to sweep the fan-shaped stream across the work in a fanwise 40 manner on each movement of the arm 83.

From Fig. 2 it will be apparent that the crank arm 85 is passing through its dead center positions when the blast streams are at the limits of their sweeping movement as represented by the 45 lines 82. This fact is taken advantage of in the present invention to cause a more equalized blasting of the articles, irrespective of their position toward or away from the center of the work holder 33. It will be apparent that more articles can be 50 suspended from the periphery of the work holder 33, than can be located near the axis of the work holder. Also, these articles at the periphery of the work holder 33 travel at a greater linear speed than do the articles near its axis of rotation.

As a consequence of this location of more articles at the outer part of the work holder, and their greater speed of travel, more blasting must be performed upon them for them to be cleaned as much as the articles nearer the center of the work holder. This result is obtained with the present 55 invention because at the outer limits, represented by the lines 82, of the blast streams, the crank arm 85 is passing through its dead center positions. At its dead center positions, the crank arm 85 causes a retarded or delayed motion of the blast streams so that they tend to dwell in the two positions at the lines 82. Therefore, although there 60 are many articles in the path of this stream and they are traveling rapidly, they receive considerable blasting. The articles close to the axis of the work holder 33 are not over blasted as the blast stream is upon them only as it is sweeping past the axis of the work holder.

To receive and collect the abrasive after it falls 65 from the articles being cleaned, the grating 16

and 17 is located over a hopper in a pit located below the floor level. This collected abrasive is fed as by a screw conveyor, to the lower end of a bucket elevator 91 (Fig. 2) inside of vertical casing 92. Elevator 91 lifts the abrasive to a point from which it descends by gravity through a closed chute 93 into the abrasive cleaner 94. This abrasive cleaner 94 may be of conventional construction.

The cleaned abrasive from cleaner 94 descends through chute 95 to the lower end of bucket elevator 96 (Fig. 2), also in the casing 92. An orifice plate 97 regulates flow through chute 95, and a valve 98 permits it to quickly cut off. Elevator 96 lifts the abrasive to a point from which it can descend by gravity through chute 99 to a distributing box 100.

From the distributing box 100, lead flexible conduits 102 to the upper blasting machines 63, and flexible conduits 103 to the lower blasting machines 64. Also leading from the distributing box 100 is a conduit 104 leading to a container 105. Abrasive is drawn from container 105, through a conduit 106 to nozzle 107 in the "touch up" chamber having side walls 15.

The abrasive is consequently recirculated through the apparatus for reuse in the blasting machines 63 and 64. The abrasive is cleaned in the cleaner 94 to remove the broken fines and also to eliminate the foreign matter removed from the articles being cleaned. Dust is removed from the housing by a suction applied at the openings 108.

In operation, the blasting machines are constantly in operation delivering abrasive and are being oscillated by means of crank arm 85 and the connecting linkage. While one work holder 33 is being rotated in this blast stream, the second work holder 33 is being unloaded of cleaned articles and loaded with uncleared articles at the open section of the housing. The third work holder 33 is at this time in the "touch up" station where its articles are being finish cleaned by an operator using the nozzle 107. As has been stated, the "touch up" operation and station can be omitted.

The time required to unload and load one work holder is about the same time required to clean the articles in the blasting station. This cleaning operation can be controlled for best results by varying the ratio between the number of times the blast streams sweep back and forth for each revolution of the work holder 33. It has been found that excellent results are obtained if there are about eight oscillations of the blast stream for each revolution of the work.

I claim:

1. Apparatus for blast cleaning articles comprising a housing closed at one section to provide a blasting station and open at one section to provide a loading station, at least two work holders, means supporting the work holders to move one into the blasting station as another is moved simultaneously therewith into the loading station, a partition connected to said means and located between each pair of work holders to cooperate with the housing in sealing relation and segregate the blasting station, said housing having a vestibule in open communication with said blasting station, an oscillatable plate in said vestibule having a sealing contact with the vestibule wall as it oscillates, abrasive projecting means supported by said plate and delivering abrasive at blasting velocity into the blasting station to clean the articles, and means for oscillating said plate to sweep the abrasive stream back and forth over the articles in the blasting station.

2. Apparatus for blasting cleaning articles comprising a generally cylindrical upright housing closed at one section to provide a blasting station and open at another section to provide a loading station, at least two work holders, means supporting the work holders for movement in a circle about the axis of said housing so that one work holder moves into the blasting station as another is moved simultaneously therewith into the loading station, a partition connected to said means and located on opposite sides of each work holder to move with them, said partitions extending into sealing contact with the housing to segregate the blasting station, said housing having a vestibule in open communication with said blasting station, an oscillatable plate in said vestibule having a sealing contact with the vestibule wall as it oscillates, abrasive projecting means supported by said plate and delivering abrasive at blasting velocity into the blasting station to clean the articles, and means for oscillating said plate to sweep the abrasive stream back and forth over the articles in the blasting station.

3. Apparatus for blasting cleaning articles comprising a generally cylindrical upright housing having a vestibule offset from a section of the housing which serves as a blasting station, the vestibule being in open communication with the blasting station and the side walls of the vestibule being arcuate about a vertical axis, abrasive projecting means in the vestibule projecting abrasive into said blasting station, mounting means for said abrasive projecting means and having oscillatable movement about the axis of said vestibule, said mounting means having a sealing contact with the arcuate walls of said vestibule during oscillation of the mounting means, means for oscillating the mounting means, at least two work holders, means supporting the work holders to move one into the blasting station as another is moved simultaneously therewith into the loading station, and a partition connected to said supporting means and located between each pair of work holders and extending into sealing relation with said generally cylindrical housing.

4. Apparatus for blasting cleaning articles comprising a generally cylindrical upright housing having a vestibule offset from a section of the housing which serves as a blasting station, the vestibule being in open communication with the blasting station and the side walls of the vestibule being arcuate about a vertical axis, abrasive projecting means in the vestibule projecting abrasive into said blasting station, mounting means for said abrasive projecting means and having oscillatable movement about the axis of said vestibule, said mounting means having a sealing contact with the arcuate walls of said vestibule during oscillation of the mounting means, means for oscillating the mounting means, at least two work holders, means supporting the work holders to move one into the blasting station as another is moved simultaneously therewith into the loading station, a partition connected to said supporting means and located between each pair of work holders and extending into sealing relation with said generally cylindrical housing, and means for rotating the work holder in the blasting station.

5. Apparatus for blasting cleaning articles comprising a generally cylindrical upright housing having a vestibule offset from a section of the housing which serves as a blasting station, the vestibule being in open communication with the blasting station and the side walls of the vestibule being arcuate about a vertical axis, abrasive

projecting means in the vestibule projecting abrasive into said blasting station, mounting means for said abrasive projecting means and having oscillatable movement about the axis of said vestibule, said mounting means having a sealing contact with the arcuate walls of said vestibule during oscillation of the mounting means, means for oscillating the mounting means, at least two work holders, means supporting the work holders to move one into the blasting station as another is moved simultaneously therewith into the loading station, and a partition connected to said supporting means and located between each pair of work holders and extending into sealing relation with said generally cylindrical housing, said oscillating means serving to cause the blast stream to dwell upon the extreme lateral limits of the oscillations.

6. Apparatus for blasting cleaning articles comprising a generally cylindrical upright housing having a vestibule offset from a section of the housing which serves as a blasting station, the vestibule being in open communication with the blasting station and the side walls of the vestibule being arcuate about a vertical axis, abrasive projecting means in the vestibule projecting abrasive into said blasting station, mounting means for said abrasive projecting means and having oscillatable movement about the axis of said vestibule, said mounting means having a sealing contact with the arcuate walls of said vestibule during oscillation of the mounting means, means for oscillating the mounting means, at least two work holders, means supporting the work holders to move one into the blasting station as another is moved simultaneously therewith into the loading station, a partition connected to said supporting means and located between each pair of work holders and extending into sealing relation with said generally cylindrical housing, and means for rotating the work holder in the blasting station, said oscillating means serving to cause the blast stream to dwell upon the extreme lateral limits of the oscillations.

7. Apparatus for blasting cleaning articles comprising a generally cylindrical upright housing having a vestibule offset from a section of the housing which serves as a blasting station, the vestibule being in open communication with the blasting station and the side walls of the vestibule being arcuate about a vertical axis, abrasive projecting means in the vestibule projecting abrasive into said blasting station, mounting means for said abrasive projecting means and having oscillatable movement about the axis of said vestibule, said mounting means having a sealing contact with the arcuate walls of said vestibule during oscillation of the mounting means, means for oscillating the mounting means, at least two work holders, means supporting the work holders to move one into the blasting station as another is moved simultaneously therewith into the loading station, a partition connected to said supporting means and located between each pair of work holders and extending into sealing relation with said generally cylindrical housing, and means for rotating the work holder in the blasting station, said oscillating means including a constantly rotating crank arm having an operating connection to said mounting means, the dead center positions of said crank arm corresponding to the extreme positions of the oscillations of the mounting means to cause the blast stream to dwell in these positions.

8. Apparatus for blast cleaning articles com-

prising a generally cylindrical upright housing providing at intervals about 120° apart, a closed blasting station, a closed touch-up station, and an open loading station, three work holders, means at the axis of the housing supporting said work holders about 120° apart so that one is in each of said three stations, said means mounting said work holders for rotation about the axis of the housing to advance them simultaneously through said stations, upright partitions supported by said means midway between the work holders and extending into sealing relation with the cylindrical wall of the housing to segregate the three stations, and means for projecting abrasive at blasting velocity upon the articles in the blasting station.

9. Apparatus for blast cleaning articles comprising a generally cylindrical upright housing providing at intervals about 120° apart, a closed blasting station, a closed touch-up station, and an open loading station, three work holders, means at the axis of the housing supporting said work holders about 120° apart so that one is in each of said three stations, said means mounting said work holders for rotation about the axis of the housing to advance them simultaneously through said stations, upright partitions supported by said means midway between the work holders and extending into sealing relation with the cylindrical wall of the housing to segregate the three stations, said work holders being supported for rotation about a vertical axis centrally through the work holders, means for rotating the work holders when in the blasting station, means for projecting abrasive at blasting velocity upon the articles in the blasting station, and means for oscillating the blasting apparatus to sweep the abrasive stream back and forth over the articles in the blasting station.

10. Apparatus for blast treating articles comprising a housing embracing a blasting station, said housing having a vestibule in open communication with said blasting station, an oscillatable plate in said vestibule having a sealing contact with the vestibule wall as it oscillates, abrasive projecting means supported by said plate and delivering abrasive at blasting velocity into the blasting station, and means for oscillating said plate to sweep the abrasive stream back and forth over articles being treated in said blasting station.

11. Apparatus for blast treating articles comprising a housing embracing a blasting station, means for supporting articles to be blasted in said blasting station, said means being mounted for rotation about a vertical axis, said housing having a vestibule in open communication with said blasting station, an oscillatable plate in said vestibule mounted to oscillate about a vertical axis and having a sealing contact with the vestibule wall as it oscillates, abrasive projecting means supported by said plate and delivering a stream of abrasive at blasting velocity into the blasting station, and means for oscillating said plate to sweep the abrasive stream from side to side along the path of rotation of articles carried by said supporting means.

12. Apparatus for blast treating articles comprising a housing embracing a blasting station, said housing having a vestibule in open communication with said blasting station, an oscillatable support in said vestibule, a plurality of centrifugal projectors mounted on said support for projecting into said blasting station fan-shaped streams of treating particles oriented in generally parallel planes, and means for oscillat-

ing said support about an axis generally parallel to the planes of said streams to sweep the projected streams back and forth over articles being treated in said blasting station.

13. Apparatus for blast treating articles comprising a housing embracing a blasting station, said housing having a vestibule in open communication with said blasting station, an oscillatable support in said vestibule, a plurality of centrifugal projectors mounted on said support for projecting into said blasting station fan-shaped streams of treating particles oriented in generally vertical planes, and means for oscillating said support about a vertical axis to sweep the streams back and forth over articles being treated in said blasting station.

14. Apparatus for blast cleaning articles comprising a housing embracing a blasting station, a work support therein, means for rotating said work support about a vertical axis, said work support comprising means for supporting a plurality of individual articles in spaced relation to said vertical axis to cause the same to travel thereabout, said housing having a vestibule in open communication with said blasting station, a support in said vestibule oscillatable about a vertical axis, particle projecting means carried by said support and directed to discharge a stream of particles at blasting velocity into said blasting station, and means for oscillating said support about its vertical axis to swing said stream from side to side along the path of travel of articles carried toward, past and away from said projecting means by said supporting means.

15. Apparatus for blast cleaning articles comprising a housing embracing a blasting station, a work support therein, means for rotating said work support about a vertical axis, said work support comprising means for supporting a plurality of individual articles in spaced relation to said vertical axis to cause the same to travel thereabout, said housing having a vestibule in open communication with said blasting station, a support in said vestibule oscillatable about a vertical axis, particle projecting means carried by said support and directed to discharge a stream of particles at blasting velocity into said blasting station, and means for oscillating said support about its vertical axis to swing said stream from side to side along the path of travel of articles carried toward, past and away from said projecting means, said oscillating means being timed to cause the blast stream to dwell at the lateral limits of its oscillations during which it is directed toward articles spaced most substantially from said axis.

16. Apparatus for blast cleaning articles comprising a housing embracing a blasting station, a work support therein, means for rotating said work support about a vertical axis, said work support comprising means for supporting a plurality of individual articles in spaced relation to said vertical axis to cause the same to travel thereabout, said housing having a vestibule in open communication with said blasting station, a support in said vestibule oscillatable about a vertical axis, particle projecting means carried by said support and directed to discharge a stream of particles at blasting velocity into said blasting station, and means for oscillating said support about its vertical axis to swing said stream from side to side along the path of travel of articles carried toward, past and away from said projecting means by said supporting means, said oscillating means being timed to oscillate said blast

stream a plurality of times for each rotation of said work support.

17. Apparatus for blast cleaning articles comprising a housing embracing a blasting station, a work support therein, means for rotating said work support about a vertical axis, said work support comprising means for supporting a plurality of individual articles in spaced relation to said vertical axis to cause the same to travel thereabout, said housing having a vestibule in open communication with said blasting station, a support in said vestibule oscillatable about a vertical axis, particle projecting means carried by said support and directed to discharge a stream of particles at blasting velocity into said blasting station, and means for oscillating said support about its vertical axis to swing said stream from side to side along the path of travel of articles carried toward, past and away from said projecting means by said supporting means, said oscillating means being timed to cause the blast stream to dwell at the lateral limits of its oscillations during which it is directed toward articles spaced most substantially from said axis, and to oscillate said blast stream between said limits a plurality of times for each rotation of said work support.

18. Apparatus for blast cleaning articles comprising a generally cylindrical upright housing providing at intervals, a first blasting station, 30 a second blasting station, and an open loading station, at least three work holders, means at the axis of the housing supporting said work holders so that one is in each of said three stations, said means mounting said work holders for rotation 35 about the axis of the housing to advance them simultaneously through said stations, upright partitions supported by said means midway between the work holders and extending into sealing relation with the cylindrical wall of the housing to segregate the three stations, means for projecting abrasive at blasting velocity upon the articles in the blasting stations at last one of said projecting means comprising a centrifugal projector oriented to project its fan-shaped blast 40 stream in a vertical plane, and means for oscillating said centrifugal projector about a vertical axis to sweep said fan-shaped stream back and forth over the articles being blasted.

19. Apparatus for blast cleaning articles comprising a generally cylindrical upright housing providing at intervals, a first blasting station, a second blasting station, and an open loading station, at least three work holders, means at the axis of the housing supporting said work holders 55 so that one is in each of said three stations, said means mounting said work holders for rotation about the axis of the housing to advance them simultaneously through said stations, upright partitions supported by said means midway between the work holders and extending into sealing relation with the cylindrical wall of the housing to segregate the three stations, said work holders being supported for rotation about a vertical axis centrally through the work holders, means for rotating the work holders when in the blasting station, a centrifugal projector oriented 60 to direct its fan-shaped stream in a vertical plane; for projecting abrasive at blasting velocity upon the articles in the first blasting station, means for oscillating said centrifugal projector about a vertical axis to sweep the fan-shaped stream back and forth fanwise over the articles in said blasting station, and means for projecting particles at blasting velocity upon the articles in the second blasting station.

20. In a blasting machine, a work holder, a centrifugal projector positioned to blast work carried thereby, said projector being oriented to direct its fan-shaped stream against work carried by said holder, and means for turning said centrifugal projector in a direction to move one end of its rotor axis toward and the other away from the work to sweep the fan-shaped stream fanwise across the work.
